CENTRIFUGAL METHOD AND APPARATUS
THEREFOR

Henry Burdett Cleveland, New York, N. Y.

Application May 28, 1934, Serial No. 727,959

2 Claims. (Cl. 210—64)

This invention relates to a process and apparatus for isolating the heavier constituents from a mixture, and more specifically to a process and centrifugal apparatus for dewatering material.

5 This application is a continuation of my co-pending application Serial Number 667,347.

In general, it is an object of the invention to provide a dewatering process and apparatus therefor, which will efficiently perform the purpose for which it is intended, which is simple and economical of construction, which can be conveniently and safely operated and which can be readily manufactured and assembled.

10 Another object of the invention is to provide a centrifugal dewatering device which will continuously remove the heavier material; and to provide such a device which will have its supply cut off automatically when it is not removing the heavier material rapidly enough, or one which 15 will, under such circumstances, regulate the rate of removal of the heavier material.

Another object is to provide a device wherein centrifugally-separated heavier material will never have a centripetal motion, wherein the lighter material does not pass through the previously-separated heavier material, wherein the caked heavier material is forced out of the device, while the latter is in motion, by a force other than centrifugal.

20 Another object is to provide a centrifugal device having continuously-acting, cake-expressing elements rotatable simultaneously about the centrifugal axis and about their own axes, which are at an angle with said axes; one wherein said elements are operated from the centrifugal axis, and one wherein their motion about their own axes is derived by planetary action from the principal centrifugal rotation.

Another object of the invention is to provide 25 a centrifugal device having an annular port coaxial with the centrifugal axis, said port being opened and closed while said device is rotating, and by means rotating with said device and operated from within said device.

Another object is to provide a centrifugal device having valves rotatable about the centrifugal axis, which valves may be operated independently of the rotation of the device and which may be operated automatically according to the amount 30 of sludge which has been pressed into a cake.

Other objects of the invention will in part be obvious and will in part appear hereinafter.

The invention accordingly comprises the several steps and the relation and order of one or more of such steps with respect to each of the others, and the apparatus embodying features of construction, combinations of elements and arrangement of parts which are adapted to effect such steps, all as exemplified in the following de-

tailed disclosure, and the scope of the application of which will be indicated in the claims.

For a fuller understanding of the nature and objects of the invention reference should be had to the following detailed description taken in connection with the accompanying drawings, in which:

Fig. 1 is a plan view of the central portion of one form of device embodying the invention, a portion being cut away and partly in section; 10

Fig. 2 is a telescoped plan view of the ends of the device shown in Fig. 1, a portion being cut away and partly in section;

Fig. 3 is a view in elevation of a section of the device shown in Fig. 1, taken along the lines 3—3, 15 partly in detail and partly in section;

Fig. 4 is a view in elevation of a detail of the device shown in Fig. 1, taken along the lines 4—4;

Fig. 5 is a view in elevation of a casing for the device shown in Fig. 1; 20

Fig. 6 is a view in elevation of the device shown in Figs. 1 and 2, on a reduced scale, together with certain motive means;

Fig. 7 is a view in elevation, similar to Fig. 6, of a modification of the device shown in Figs. 1—6; 25

Fig. 8 is a view in elevation, partly in section, of a portion of the device shown in Fig. 7;

Fig. 9 is a view in elevation, partly in section, similar to Fig. 1, of a modification of the device shown in Fig. 1; and 30

Fig. 10 is a view in section of a detail of the device shown in Fig. 1.

In the drawings, 10 denotes the main input power shaft to which is secured in any convenient manner a tubular shaft 11, which may, for the purposes of assembling, comprise several annular portions. Attached to the tubular shaft and rotatable therewith is a casing 12, which forms an enclosed chamber about said shaft, and certain portions of which are spaced farther from the axes of said shaft than other portions. The purpose of these more removed portions, preferably positioned centrally along the axis of the machine, is to receive the heavier material which is thrown outwardly centrifugally from the input mixture which is led in through a plurality of passageways 13, which pierce the tubular shaft 11, each of which has an entrance near an end of that shaft. The casing is shaped with slanting portions to facilitate the movement of the heavy material toward the outer portions. 45

These outer portions of the casing are provided with means for continuously disposing of the heavier material. These means comprise a plurality of openings 14, which preferably lie in a plane perpendicular to the axis of the device. There may be a plurality of sets of openings, each set in its own plane. Means are provided within the openings for regulating or assisting the passage therethrough of the heavy material and may 50

take the form of a worm 15, the threads of which preferably have a small pitch and lead outwardly. The worms may be given a motion independent of the rotation of the tubular shaft and its casing in any convenient manner, for example, they may be attached to shafts 16, which are radially disposed with respect to the tubular shaft and which, aside from a rotation about their own axes, are fixed with respect to said tubular shaft and 5 10 15 20 25 30 35 40 45 50 55 60 65 70 75

rotate with the tubular shaft about its axis. The independent motion of the shafts 16 upon their own axes may be obtained as desired. As shown in the drawings, they are provided with pinions 17, which mesh with the double ring gear 18, which is splined to a subsidiary power shaft 19, the latter being preferably coaxial with, and supported on, tapered bearings within the tubular shaft 11.

There may also be an adjusting bearing between the tubular shaft and the shaft 19, which bearing may be regulated by the ring nut 20, so as to take up any wear. It will be seen that when the shafts 10 and 19 have the same angular velocity, the radial shafts 16 will not rotate on their own axes and the worms will not act as conveyors to remove material through the openings 14. At certain times it is not desirable that material be removed through those openings, and hence means are provided for giving the shafts 10 and 19 equal angular velocities. These means may be a pair of synchronous electric motors 20 and 21, attached respectively to the shafts 10 and 19. When it is desired to operate the worms or screw conveyors, the speed of one of the motors may be changed in any suitable fashion, whereby the differential angular velocity assumed in a planetary fashion by the pinions 17, is given to the worms 15; or their result may be effected by means of a hydraulic brake operated to reduce the angular velocity of one of the tubular shafts.

Intake pipes 22 spaced about the axis of the machine lead into an outwardly-opening annular chamber 23 in the tubular shaft, from which chamber the various passageways 13 lead. The input mixture is thus carried from the pipes 22 through the passageways 13 into the main centrifugal chamber between the tubular shaft 11 and its casing 12. The passageways 13 are preferably so positioned with reference to the axis of rotation and to the position of the zone of first egress of the effluent from the casing as to provide for the discharge from these passageways into the casing of incoming material at points farther removed from the axis of rotation than the inner face of revolving material previously introduced into the casing. This method of inletting material to be deliquitated prevents spraying and cascading of such material within the casing and insures that a maximum time will elapse in the passage of liquid material through the casing by preventing rapid flow of the inletted material over the inner face of material revolving within the casing to the effluent outlets. The effectiveness of the centrifugal separation of solids from liquids is thus substantially increased. Other intake pipes 24 for cleansing fluid similarly are spaced around the axis of the machine and lead into a chamber 25, which will be described below. The pipes 22 and 24 may be concentrated above the axis of the machine to counteract any tendency of the material in the machine to pile up in the bottom of the machine due to gravity. The spacing of the pipes may be adjustable.

Means are provided for receiving the effluent

from which the heavy material has been centrifugally separated. These may comprise annular receiving rings 26 at the ends of the tubular shaft, which are fixed with respect to that shaft and which are adapted to receive the discharge effluent through a plurality of outlets 27, which lead out of the main chamber within the casing 12 and at a point nearer the axis of the machine than the openings 14.

The foregoing parts are adapted for separating out the heavier material centrifugally and for pressing that material into a cake. If it is desired to filter the effluent before it passes through the outlets 27, means to this end may be provided. A preferred form of filtering means is that described in my co-pending application Serial No. 667,347. Filter baskets, generally shown at 28, may be attached to the tubular shaft at each end thereof. A plurality of filter blades 29 placed around the outer periphery of the tubular shaft 20 and preferably at a slight angle with the axis thereof, intercepts the flow of effluent from the chamber within the casing 12 to the outlets 27, the portions of the blades toward the ends of the tubular shaft being more removed from its axis. The blades may be extremely thin and flexible and only a few thousandths of an inch in thickness. They are provided along one face thereof with washers, which are strung upon endless circular rods 30 and keep the blades separate in 30 their open-non-filtering and filtering positions.

Means are provided for regulating the opening or closing of the blades. Bars 31 are attached to the tubular shaft by any convenient means such as the nuts 32. These bars extend along 35 the blades at an angle similar to that at which the blades are placed. The lower inclined ends of the bars 31 have seats cut therein on their exterior faces and a plurality of endless hoops 33 are seated in said seats. These hoops may be 40 welded in position. The interior faces of the lower bars have a plurality of similar seats cut therein, which receive a plurality of endless hoops 34, which also may be welded in position. Thus the bars and the hoops 33 and 34 are in the form 45 of an integral pressure basket, and when in operative position, the outer edges of the filter blades 29 are always in contact with the inner surfaces of the pressure hoops 34. The pressure basket may be moved axially relative to the blades by 50 adjustment of the screws 32. Means not shown may be provided for adjusting all of the bars 31 together and automatically, if desired. The more the bars 31 are pulled toward the ends of the device, the tighter the rings 34 will bear 55 against the blades 29 and cause the latter to be flexed into the closer filtering relation shown in Fig. 4. Passageways 35 lead from the chamber 25 through the tubular shaft 11 to the blades so that cleaning fluid coming from the tubes 24 may be 60 passed over the filter blades when they are to be cleaned.

The rotatable casing 12 may be surrounded by a fixed casing 36 adapted to receive the discharged cake and to guide the latter away from 65 the rotating mechanism.

The filter-blade basket may be made up of several thousand thin metal strips between which the effluent is forced backward toward the central shaft by the centripetal force developed as 70 the liquid which contains the solids is revolved in the casing or drum at high speed. In the case of a device of the relative dimensions shown in the drawings, which has a blade basket of thirty-two inches diameter, one and one-quarter miles of 75

orifice length are provided, with each orifice 0.003 inch wide and a total opening equal to the area of a 17-inch diameter pipe.

Switch means may be provided in the excess 5 sludge channel for regulating the operation of the device. They may be electrical and may be operated by the specific gravity of the excess sludge. If the cake is built up faster than it is removed and some of the sludge passes out to the station- 10 ary excess sludge channels 26', the switch is tripped and changes the speed of the motor 21 to increase the speed of the screw conveyors and/or cuts down the rate of inflow of sludge and/or causes the introduction of cleaning fluid through 15 the filter and/or regulates the position of the pressure basket about the filter blades so as to change the size of the orifices between the latter.

In Fig. 10 suitable switch means are illustrated 20 for effecting the desired control of the rate of inflow of sludge, the introduction of cleaning fluid through the filter, the position of the pressure basket about the filter blades, and/or an alteration 25 in the rate of discharge of the dewatered material. These switch means may comprise a pivoted member 90 mounted to pivot about the axis 91 and extending into the excess sludge channel 26'. This pivoted member is preferably so mounted as to remain substantially in the position shown in solid lines in Fig. 10 until an over- 30 flow of sludge passes through the channel 26' and by impact against the member 90 sends it into position, as shown for example in the dotted lines in Fig. 10, such that the member makes contact 35 with an electrical contact element 92. The pivoted member and the electrical contact may be suitably mounted in an electrical circuit in any obvious manner in such a way that when the element 90 makes contact with the element 92 the circuit is closed. The closing of the circuit may 40 affect the driving elements of the dewatered material discharge devices to increase or decrease the speed of discharge, and it may also affect the operation of an intake valve to regulate the inflow of sludge, etc.

The operation of the device is as follows:

The material to be dewatered, such as sewage sludge, is fed into the drum through several stationary pipes from an overhead tank. Solids are thrown outward by centrifugal force to the ports 50 housing the screw conveyors as shown. The liquid in the material is forced backward and passes between the filter blades and thence to the effluent channels at each end of the drum.

The screw conveyors cut a thin ribbon of cake 55 or dried material, continuously, from the mass of dried material in the drum along its outer face where the dewatering effect is most complete. To start the process caps 14' are screwed and bolted over the ports 14, the two shafts 10 and 19 are 60 revolved at the same speed, and sludge is fed into the drum. When the drum is filled with cake it is stopped, the caps are removed and not used again. The shafts are rotated with the one actuating the cake discharge mechanism run at slightly lower 65 speed than the main drive, and sludge is again fed into the drum.

Any retardation of flow of effluent through the filter blades by reason of the building back against the filter-blade basket of thick sludge or 70 cake is immediately and automatically corrected by the effect of the resulting overflow of some of the sludge which is being fed into the drum. This overflow of sludge, on its passage to the stationary channels encircling the ends of the 75 drum, trips an electric switch and partly closes

the sludge inlet valve. The sludge inlet valve at once begins to open to full inlet position, but in the meantime the thick sludge has moved outward an inch or more, wash water has been automatically thrown against the inner face of 5 the filter-blade basket, and any solids remaining between the filter blades have been washed back into the drum. The filter-blade basket is thus automatically cleaned whenever necessary to maintain full, average inletting rates and without the creation of a secondary problem of disposing of filter-clogging material.

The device shown in Figs. 7 and 8 is similar to the device shown in Figs. 1-6, except that a modification of the means within the openings 15 14 is provided for regulating or assisting the passage therethrough of the heavy material. These means take the form of a plurality of poppet valves 40. The valves may be given a motion independent of the rotation of the tubular shaft 20 11 and its casing 12 in any convenient manner. For example, they may be attached to valve stems 41, which are radially disposed with respect to the tubular shaft 11 and which, aside from a displacement along their own axes, are 25 fixed with respect to said tubular shaft and rotates with said tubular shaft about its axis.

The independent motion of the stems 41 along their axes may be obtained as desired. As shown 30 in the drawings, they are each provided with a cam 42, which co-acts with a cam 43 on a bell crank 44, pivoted at 45 to the tubular shaft 11 or an extension thereof. The other arm 46 of the bell crank may contact with a ring 47 on a subsidiary shaft 48. The ring 47 may have a 35 cam surface against which the arm 46 slides. The subsidiary shaft 48, located within tubular shaft 11, may be given an axial motion. As shown, the shaft 48 is fixed to the shaft 11 and rotates therewith. The shaft 48 extends through 40 a fixed cylinder 49 and has a piston 50 rotatable therewith and slidable therewith within the cylinder 49. The shaft 48 also extends through a chamber 51 and at least into a second chamber 52. Means, such as the pipes 53 and 54 provide 45 inlets through the walls of these chambers respectively, whereby fluid pressures may be set up within the chambers. Passageways 55 and 56 lead respectively from the chambers through the shaft 48 into the piston cylinder 49, one on 50 each side of the piston 50.

The operation of the device shown in Figs. 7 and 8 is as follows:

Assuming that the valves 40 are seated so as to close the openings 14, sludge is admitted to 55 the machine and the latter rotated until a sufficient amount of cake has been deposited against the casing 12 and compressed to form a cake of desired properties. Thereupon fluid pressure is 60 admitted into the chamber 52. This pressure is transmitted to the left-hand side of the piston 50, which latter is forced thereby toward the right in the cylinder 49 and carries with it the subsidiary shaft 48. The ring 47 is moved with 65 the shaft 48 to the right and causes a motion of the arm 46 of the bell crank 44. This latter motion is transmitted pivotally to the cam 43 which, pressing against the cam 42, causes the latter and its attached valve stem 41 to move radially 70 inward with respect to the axes of the machine. The valve 40 is thus lifted away from its seat so as to permit the cake, under the influence of centrifugal action, to pass out of the opening 14. The ring 47 acts similarly upon all of the plural- 75

ity of bell cranks, so that all of the valves 40 may be opened simultaneously.

Where there are a plurality of sets of openings 14, each set being in one of a plurality of parallel planes perpendicular to the axis of the machine, the crank arms 44' which actuate the valves 40' in one set, may be provided with spur-gear segments 57', adapted to mesh with spur-gear segments 57 on the respective bell cranks 44. A motion transmitted from the ring 47 to the bell cranks 44 is thus also imparted to the bell cranks 44'. The valves 40' are in this way all opened simultaneously with the valves 40.

If desired, the ring 47 may ride on the subsidiary shaft 48 on bearings. The latter shaft may be stationary and supported on bearings within the tubular shaft 11.

If desired, the valves, instead of being within the casing 12, may be without the casing 12 and supported on their stems which would, in that case, pass from the central portion of the openings 14. These valves may be automatically controlled by mechanisms similar to those shown in Fig. 8, so as to operate when a cake of a predetermined amount or density has been formed, the centrifugal force of the valve and cake overcoming, for example, a certain fluid pressure in the cylinder 49 on one side of the piston 50. The operation may be controlled by springs.

The device shown in Fig. 9 is similar to the device shown in Figs. 1-6, except that the means for regulating the passage of the caked material out of the rotating drum is modified. The annular openings 114 and 114' extending circumferentially along the periphery of the casing 12 take the place of the openings 14 described above. There may be one or more of these openings 114. Suitable means for exposing and covering the openings 114 and 114' may be operated independently of the rotation of the tubular shaft 11 and its casing 12. As shown, there are two openings 114 and 114'. As mentioned before, the tubular shaft 11 may comprise, for purposes of assembling, the several annular elements 60, 62, and the annular element 61 intermediate the elements 60 and 62. The casing 12 is cut away at 63 and 64, leaving a relatively broad annular space between 63 and 64. The elements 60, 61 and 62 extend out toward and occupy in general this broad space. The element 60 does not quite extend to the edge 63 and there is an annular opening 114 thus left therebetween. Similarly there is an opening 114' between element 62 and edge 64. These openings act as exits from the chamber within the casing 12 and are covered and uncovered by means now to be described.

The elements 60, 61 and 62 are cut away in portions near their radial extremities so as to form two annular chambers, one lying between elements 60 and 61, and one lying between elements 61 and 62. In each chamber there is a respective piston member 65 and 65' extending around and movable parallel to the axis of the tubular shaft 11. Arms 66 and 66', integral respectively with the pistons, are adapted, for certain positions of said pistons, to cover the respective openings 114 and 114'.

Means are provided for introducing an actuating material into the aforementioned chambers on either side of the pistons 65 and 65', through any suitable conduits. As shown, the main power input shaft 10 extends axially through the tubular shaft 11 and the components 60, 61 and 62 of the latter, and extends into a pair of fixed 75 separate chambers 67 and 68. A channel 69 leads

from chamber 67 through shaft 10, divides and passes through the tubular shaft 11 and elements 60 and 62, and opens into the chambers in which the pistons 65 and 65' are located, one end of said channel terminating on one side of piston 65 and the other end of said channel terminating on the axially-opposite side of piston 65'. A channel 70 leads from chamber 68 through shaft 10, and element 61 divides so as to terminate on the other sides of said pistons 65 and 65'.

The operation of the device shown in Fig. 9 is as follows:

Fluid pressure, for example, city water, is admitted to chamber 68 and is transmitted through the channel 70 to the left-hand side of piston 65 and to the right-hand side of piston 65', which latter are thereby moved so that the arms 66 and 66' close the openings 114 and 114'. Sludge is admitted to the main chamber in casing 12 and the entire machine rotated until a cake is built up on the inside of the casing 12. Then the chamber 68 may be opened to atmospheric pressure and a pressure greater than atmospheric, for example, city water, may be admitted to chamber 67. The latter pressure is transmitted through channel 69 to the right side of piston 65 and to the left side of piston 65', which pistons are thereby moved so as to open the openings 114 and 114'.

The regulation of the pressure which operates the arms or gates 66 and 66' may be automatic and at regular intervals, and the intervals may be controlled by the depth of cake formed or by the overflow from the device as explained in connection with Fig. 1.

Since certain changes in carrying out the above process and in the constructions set forth, which embody the invention, may be made without departing from its scope, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. In a device of the character described, the combination comprising means adapted for supplying material to be deliquidated, means adapted for separating centrifugally therefrom at least a part of the solids therein, means adapted for removing at least a portion of said separated solids continuously, and automatic means adapted, when the unremoved separated solids amount to a predetermined quantity, for varying the rate of operation of said removing means.

2. In a device of the character described, the combination comprising a rotatable casing provided with passageways substantially radial to the axis of rotation, means extending radially from said axis and through said passageways and adapted for controlling the passage of material through said passageways, a plurality of cylindrically-arranged blades forming a filter basket nearer the axis of rotation of said casing than said passageways, and means adapted for delivering material from said basket to a point without said casing.

HENRY BURDETT CLEVELAND.
